UNITED STATES PATENT OFFICE.

DWIGHT S. RICHARDSON, OF NEW YORK, N. Y.

DESIGN FOR A FIRE-POT.

SPECIFICATION forming part of Design No. 33,389, dated October 16, 1900

Application filed September 15, 1900. Serial No. 30,180. Term of patent 14 years.

To all whom it may concern:

Be it known that I, DWIGHT S. RICHARDSON, of New York, county of New York, and State of New York, have invented and produced a new and original Design for Fire-Pots, of which the following is a specification, reference being had to the accompanying drawing, forming a part of the same.

The figure of the drawing represents in perspective a fire-pot embodying the present design.

The leading or characteristic feature of the design is the circular-body portion of the fire-pot, slightly tapered from top to bottom and having the two outwardly-curved projections extending beyond the general contour at the top thereof.

The letter A indicates the body portion of the fire-pot, tapered slightly from top to bottom, having the outwardly and upwardly extending flange B at the top, and C the two outwardly-curved projections merging into the upper edge of the body portion and flange B. The projections C taper toward the bottom and merge gradually into the body portion and flange.

I claim—

The design for a fire-pot herein shown and described.

DWIGHT S. RICHARDSON.
